CIRCUIT CONTROL SYSTEM

Richard B. Hunter, Shorewood, Wis., assignor to
 Cutler-Hammer, Inc., Milwaukee, Wis., a corporation of Delaware

Application November 14, 1940, Serial No. 365,636

11 Claims. (Cl. 175—312)

This invention relates to improvements in circuit control systems and is particularly applicable to illumination control systems comprising a plurality of lamp circuits with provision for presetting a plurality of intensities of illumination of each circuit and effecting transition from one preset intensity to another at selective rates which may differ from each other for different circuits.

In my co-pending application Serial No. 280,448, filed June 22, 1939, now Patent No. 2,225,994 of December 24, 1940, I have disclosed a system of the aforementioned character in which each of a plurality of lamp circuit controllers may be selectively grouped and the respective groups are connected to common master controllers, one for each group and each scene to be preset, so as to provide for transition from one scene to another at different selected rates for the respective groups. In accordance with the present invention each lamp circuit controller is provided with a plurality of scene controllers and may be connected to the latter selectively through a fader which provides for transition of the circuit from one scene controller to another, while the faders for the several lamp circuits may be connected selectively to one of a plurality of operators to be driven at selected speeds, so as to operate all of the faders connected to one operator at the same speed, while the different operators operate simultaneously at different speeds to transfer the control of the individual lamp circuits from one intensity control to another.

An object of the invention is to provide a simple system of the aforementioned character which is applicable to any of a variety of types of voltage control apparatus for the lamp circuits.

Another object is to provide a system of the aforementioned type including for each lamp circuit a plurality of individual controls, whereby transition of the intensity of illumination of an individual circuit from one preset to another is effected gradually and continuously at a selected rate.

Another object is to provide a system wherein if desired any of the individual circuits may be controlled independently of any of the joint control means.

Other objects and advantages will hereinafter appear.

The accompanying drawings are illustrative of a system embodying the invention.

In the drawings,

Figure 1 is a circuit diagram of the system which comprises a plurality of lamp circuits each controllable selectively by a plurality of lamp cir-

cuit potentiometers. The respective potentiometers of the various circuits are arranged so as to be controllable by a corresponding plurality of scene master potentiometers. Coordinated with the potentiometers of each lamp circuit is a fader by means of which the control of any lamp circuit may be transferred from one scene controller to another scene controller.

Fig. 2 shows a control panel for the system illustrated in Fig. 1, and

Fig. 3 shows a detail of the mechanism for operating the various fader potentiometers.

Referring to the diagram Fig. 1, the same illustrates a system comprising two lamp circuits 1 and 2, the intensity of illumination of which is controlled by lamp controllers 3 and 4, respectively, which may be of any suitable type; as, for example, that shown in my co-pending application Serial No. 286,848, now Patent No. 2,232,068 of February 18, 1941, which responds to the difference in output voltage between a sender potentiometer and a receiver potentiometer, one of the latter forming part of each of the controllers 3 and 4.

25 In view of the fact that the controllers for the various lamp circuits are alike, only that for the lamp circuit 1 will be described in detail. The energy for the lamps and the control circuit is supplied from the alternating current bus bars L¹ and L² as described in the aforementioned applications, Serial Nos. 280,448 and 286,848.

As will be apparent to those skilled in the art, the various elements of the illumination control system may be of a character adapted for use 35 with a source of supply of direct current.

The sender control system comprises two master sender potentiometer rheostats or autotransformers 5 and 6, respectively, which have their input terminals connected across the lines L¹ and L² and which may be used selectively for the control of scenes 1 and 2, respectively. The potentiometer 5 is provided with a movable contact 5^a and the potentiometer 6 with a movable contact 6^a by means of which variable output voltages 40 may be provided. The movable contacts 5^a and 6^a are connected to bus bars 7 and 8, respectively. The system also includes two lamp scene potentiometers for each of the lamp circuits, the scene potentiometers for circuit 1 comprising the rheostats 9 and 10 for scenes 1 and 2, respectively. The potentiometers 9 and 10 are respectively equipped with movable contacts 9^a and 10^a. A potentiometer rheostat 11 is connected between the movable contacts 9^a and 10^a. Said potentiometer rheostat is also provided with a movable 45

contact 11^a which is adapted to impress a variable output voltage upon bus bar 12, the latter being connected to the lamp controller 3 to impress thereon a variable control voltage, as will be more fully described hereinafter.

In the diagram the movable contact 11^a is shown at the extreme left so that the full potential of the movable contact 9^a is impressed upon the controller 3 and as a result the lamps 1 have impressed thereon a voltage which causes them to operate at a brilliancy depending upon the position of the contact 9^a, modified by the voltage impressed upon the potentiometer 9 by the movable contact 5^a of the potentiometer 5 through the bus bar 7, as fully described in my aforementioned applications Serial Nos. 280,448 and 286,848.

If it is now desired to enact the illumination effect for scene 2 the movable contact 6^a is moved to the desired point of the master scene potentiometer 6, so as to impress the desired voltage on the bus bar 8 which voltage is then impressed upon the lamp scene potentiometer 10. Also the movable contact 10^a is put in a position corresponding to the intensity of the lamps desired after the transfer from scene 1 to scene 2. If now the movable contact 11^a is moved at a desired rate from the extreme left hand position shown in the diagram to the extreme right hand position, the potential impressed upon the controller 3 is varied from that corresponding to the setting of the potentiometers 5 and 9 to that determined by the adjustment of the potentiometers 6 and 10.

It will be obvious that the adjustments for the other lamp circuits may be made in a similar manner.

Referring now to Figs. 2 and 3, the same illustrates the mechanism by which the movable contact 11^a and similar contacts of other lamp circuits may be grouped together and operated at preselected speeds so as to transfer simultaneously all of the lamp circuits or a selected number of lamp circuits from one scene preset to another and to operate different lamp circuits at different selective speeds.

The fader potentiometer rheostats 9 and 10 respectively and the contact bar 12 are mounted fixedly on suitable brackets 13, which in turn are mounted behind a panel 27. The movable contact 11^a which bridges the circuit between the rheostat 11 and the bar 12 is insulatedly supported by a pivot 14 on the bracket 13 by means of an insulating block 15. The pivot 14 is rigidly connected to the bracket 13. A fork 16 is pivotally attached to the insulating block 15 by means of pins 17 and 18 so that it may be oscillated or swung in either direction, from an intermediate position, at right angles to its directions of rotation about the pivot 14. The lever 16 is provided with pins 19 and 20, respectively, by means of which it may be selectively coupled to fork 21 or fork 22, which are frictionally attached by slip connections to shafts 23 and 24, respectively, to rotate therewith through a limited angle. The upper end of fork 21 (which is substantially identical in form and height with the upper end of lever 22) is broken away for purposes of illustration. The two shafts 23 and 24 may be, and preferably are, driven at different speeds by a motor 25 through suitable gearing 26, or said shafts may be operated in any other suitable or desired manner. The lever 16 is also arranged so that it may be held in its central or inter-

mediate position wherein neither the pin 19 nor the pin 20 engages its cooperating forked lever 21 or 22, so that the rheostat 11 may be directly controlled manually by means of the handle of lever 16 independently of shafts 23 and 24.

The fader rheostats for the other lamp circuits are arranged similarly to the aforesaid discussed rheostats for lamp circuit No. 1 and are mounted in groups on a panel 27 as shown in Fig. 2 10 of the drawings. The panel is provided with slots 28 for the handles of the several levers 16, the panel showing a total of seven control levers (marked 11^a, 11^b, etc.) for seven lamp circuits. As indicated in Fig. 2 the scene controllers for 15 scene No. 1 of all of the respective lamp circuits are mounted to the left of the fader controllers, 11^a, 11^b, etc., whereas the scene controllers for scene No. 2 are mounted to the right of said fader control levers.

The panel is also provided with slots 29 and 30 for the contactor handles 5^a and 6^a of the master controllers (5 and 6, Fig. 1). They are arranged on the panel above the lever handles of the respective lamp scene potentiometers and 25 it will be observed that the positions of the respective handles indicate the effect of the respective control instrumentalities.

During the enactment of scene No. 1 all of the levers of the fader potentiometers 11 are 30 normally at the left in Fig. 2 and if it is desired to transfer the illumination from scene No. 1 to scene No. 2 these levers are moved at the desired rate or rates of speed to the extreme right as aforesaid, by either coupling them with shaft 21 or with shaft 22, as shown in Fig. 3.

The gears which connect shafts 23 and 24 with the motor 25 differ from each other in size so that the two shafts operate at different speeds when the motor is energized. If it is desired to change from one scene setup to another it is only necessary to set the proper scene masters and lamp circuit potentiometers, couple the respective faders with shaft 23 or shaft 24 and energize the motor. The latter may be provided with suitable control switches for starting, stopping and reversing—as shown more or less diagrammatically at 31 in Fig. 2. This part of the equipment presents nothing novel and needs no further description.

I claim:

1. A control system, comprising a circuit to be controlled, voltage responsive means for controlling said circuit, a plurality of voltage regulators for presetting different operating values of an electrical condition of said circuit, fading means connected between said voltage regulators and said voltage responsive means and adapted upon operation to increase the effect of one and to simultaneously decrease the effect of another of said regulators upon said voltage responsive means, a plurality of means for operating said fading means, and coupling means for selectively connecting said fading means to any one of said operating means.

2. A control system comprising a circuit to be controlled, voltage responsive means for controlling said circuit, a plurality of voltage regulators for presetting different operating values of an electrical condition of said circuit, fading means connected between the output terminals of said voltage regulators and adapted upon operation to increase the effect of one and to simultaneously decrease the effect of another of said regulators upon said voltage responsive means, a plurality of

means for operating said fading means operable simultaneously at different rates of speed, and coupling means for selectively connecting said fading means to one of said operating means.

3. A control system comprising a circuit to be controlled, voltage responsive means for controlling said circuit, a pair of voltage regulators for presetting different operating values of an electrical condition of said circuit, a fader having its input terminals connected between the output terminals of said voltage regulators and its output terminal connected to said voltage responsive means and adapted upon operation to increase the effect of one and to simultaneously decrease the effect of the other of said regulators upon said voltage responsive means, a plurality of means for operating said fader, and selective coupling means for connecting it to one of said operating means.

4. In an illumination control system affording individual and joint control of the illumination intensity of a plurality of lamp circuits for the enactment of a plurality of illumination effects for different scenes, comprising, for each lamp circuit, voltage responsive means for controlling said intensity, a plurality of voltage regulators one for each of said scenes and affording a variable ratio between their respective input and output voltages, fading means connected between said voltage regulators and said voltage responsive means and adapted upon operation to increase the effect of the output voltage of one and to simultaneously decrease the effect of another of said regulators upon said voltage responsive means, a plurality of means each of which is adapted to operate any number of said fading means, and coupling means for selectively connecting any of said fading means to any one of said operating means.

5. In an illumination control system affording individual and/or joint control of the illumination intensity of a plurality of lamp circuits for the enactment of a plurality of illumination effects for different scenes, comprising, for each lamp circuit, voltage responsive means for controlling said intensity, a plurality of selectively operable voltage regulators one for each of said scenes and affording a variable ratio between their respective input and output voltages, fading means connected between the output terminals of said voltage regulators and adapted upon operation to increase the effect of one and to simultaneously decrease the effect of another of said regulators upon such voltage responsive means, a plurality of means each of which is adapted to operate any number of said fading means, said operating means being operable simultaneously at different rates of speed, and coupling means for selectively connecting any of said fading means to any one of said operating means.

6. In an illumination control system affording individual and joint control of the illumination intensity of a plurality of lamp circuits for the enactment of a plurality of illumination effects for different scenes, comprising, for each lamp circuit, a voltage regulator for controlling said intensity, a plurality of scene potentiometers, one for each of said scenes and affording a variable ratio between their respective input and output voltages, a fader potentiometer having input terminals connected between the output terminals of said scene potentiometers and its output terminal connected to said voltage regulator and adapted upon operation to increase the effect of the output voltage of one and to simultaneously decrease the effect of the output voltage of

another of said scene potentiometers upon such voltage regulator, a plurality of operating means each of which is adapted to operate all or any number of said fader potentiometers, and coupling means for selectively connecting any of said fader potentiometers to any one of said operating means.

7. In an illumination control system affording individual and/or joint control of the illumination intensity of a plurality of lamp circuits for the enactment of a plurality of illumination effects for different scenes, comprising, for each lamp circuit; a voltage regulator for controlling said intensity, a plurality of selectively operable scene potentiometers, one for each of said scenes and affording a variable ratio between their respective input and output voltages, a fader potentiometer having input terminals connected between the output terminals of said scene potentiometers and its output terminal connected to said voltage regulator and adapted upon operation to increase the effect of one and to simultaneously decrease the effect of another of said scene potentiometers upon such voltage regulator; a plurality of operating means each of which is adapted to operate all or any number of said fader potentiometers, said operating means being operable simultaneously at different rates of speed, coupling means for selectively connecting any of said fader potentiometers to any one of said operating means, and reversible means for driving said plurality of operating means.

8. In an illumination control system affording individual and/or joint control of the illumination intensity of a plurality of lamp circuits for the sequential enactment of a plurality of illumination effects for different scenes, comprising, for each lamp circuit; a voltage regulator for controlling said intensity, a pair of scene potentiometers, one for each of two sequential scenes and affording a variable ratio between their respective input and output voltages, a fader potentiometer having input terminals connected between the output terminals of said scene potentiometers and its output terminal connected to said voltage regulator and adapted upon operation to increase the effect of the output voltage of one and to simultaneously decrease the effect of the output voltage of the other of said scene potentiometers upon such voltage regulator; a pair of operating elements either of which is adapted to operate all or any number of said fader potentiometers, means including a reversible electric motor for jointly driving said pair of elements in one direction or the other between predetermined limits, said last mentioned means including means for insuring predetermined different rates of speed for the respective elements, said last mentioned means also including a slip clutch connection between each of said elements and said driving motor, and manually operable coupling means individual to each of said fader potentiometers to provide for selective connection of any of the latter to either of said operating elements, or alternatively to disconnect the respective potentiometer from both of said operating elements.

9. In an illumination control system affording individual and/or joint control of the illumination intensity of a plurality of lamp circuits for the sequential enactment of a plurality of illumination effects for different scenes, comprising, for each lamp circuit; a voltage regulator for controlling said intensity, a pair of scene potentiometers, one for each of two sequential scenes

and affording a variable ratio between their respective input and output voltages, a fader potentiometer having input terminals connected between the output terminals of said scene potentiometers and its output terminal connected to said voltage regulator and adapted upon operation to increase the effect of the output voltage of one and to simultaneously decrease the effect of the output voltage of the other of said scene potentiometers upon such voltage regulator; a pair of operating elements either of which is adapted to operate all or any number of said fader potentiometers, means including a reversible electric motor for jointly driving said pair of elements in one direction or the other between predetermined limits, said last mentioned means including means for insuring predetermined different rates of speed for the respective elements, said last mentioned means also including a slip clutch connection between each of said elements and said driving motor, manually operable coupling means individual to each of said fader potentiometers to provide for selective connection of any of the latter to either of said operating elements, or alternatively to disconnect the respective potentiometer from both of said operating elements, and means comprising a pair of adjustable and preadjusted master scene potentiometers for modifying and controlling the illumination effects preselected by the scene potentiometers for each of the respective scenes.

10. A control system, comprising a circuit to

be controlled, voltage responsive means for controlling said circuit, a plurality of voltage regulators for presetting different operating values of an electrical condition of said circuit, fading means connected between said voltage regulators and said voltage responsive means and adapted upon operation to increase the effect of one and to simultaneously decrease the effect of another of said regulators upon said voltage responsive means, a plurality of means for operating said fading means, coupling means for selectively connecting said fading means to any one of said operating means, and associated means to provide for actuation of said fading means independently of said operating means.

11. A control system comprising a circuit to be controlled, voltage responsive means for controlling said circuit, a plurality of voltage regulators for presetting different operating values of an electrical condition of said circuit, fading means connected between the output terminals of said voltage regulators and adapted upon operation to increase the effect of one and to simultaneously decrease the effect of another of said regulators upon said voltage responsive means, a plurality of means for operating said fading means operable simultaneously at different rates of speed, coupling means for selectively connecting said fading means to one of said operating means, and associated means to provide for actuation of said fading means independently of said operating means.

RICHARD B. HUNTER.
